KEYHOLE PLUG FOR CYLINDER LOCKS

Application filed September 29, 1925. Serial No. 59,345.

This invention relates to keyhole plugs for cylinder locks, an object of the invention being to provide a plug which can be inserted in a cylinder lock, which will prevent the use of the ordinary key to operate the lock, and which cannot be removed except by the insertion of a plug key.

An object of the invention therefore is to provide a plug which can be inserted in the lock and which will prevent the operation of the lock even though the user has the proper key for the lock or a master key. The uses for such a plug are many. For example, where a salesman has on display in a hotel room valuable articles, he can use such a plug to prevent the employees or tenants of the hotel from entering the room. Furthermore, a plug of this kind can be used in automobile locks, which will greatly overcome the liability of theft of the car. Also it is to be understood that the invention can be applied to any cylinder lock for any use to which it may be put.

With these and other objects in view, the invention consists in certain novel features of construction and combinations and arrangements of parts, which will be more fully hereinafter described and pointed out in the claims.

In the accompanying drawings—

Figure 1 is a view in longitudinal section through a cylinder lock showing my improved plug in operative position therein;

Figure 2 is a similar view showing the plug key in position for removal of the plug;

Figures 3 and 4 are perspective views of the plug and the plug key, respectively;

Figure 5 is a view in transverse section through the registering plug and plug key, the section being taken on the line 5—5 of Figure 2;

Figure 6 is an end view of a cylinder lock showing my improved plug in operative position therein.

My invention includes the provision of a plug 1 and a plug key 2. I employ this term "plug key" to distinguish it from the ordinary key designed to operate the lock as the plug key is only used for removing the plug and is in no sense designed for operating the lock.

3 represents a cylinder lock of ordinary or standard construction. Such a lock is provided with sectional pin tumblers 4, pressed by springs 5 into locking engagement with a rotary barrel 6. This barrel has a keyhole 7 for the reception of a key (not shown) which functions to properly register the pin tumblers and allow the barrel to be turned.

To prevent the use of the ordinary key or skeleton key I provide my improved plug 1 which is adapted to be inserted into the key-hole slot or groove 7 of the lock and has a fixed disk or plate 8 at its outer end which bears against the face of the lock and which has an opening 9 therein of proper shape to receive the plug key 2.

This plug 1 is made of proper shape in cross section to fit the key receiving groove or slot 7 and at its inner end is formed with an upwardly projecting tongue 10 having an inclined or cam face 11 which functions to force the pin tumblers 4 upwardly when the plug 1 is inserted in the lock. As this tongue 10 passes the tumblers 4, the latter will move downwardly into the path of the tongue and prevent the removal of the plug, as clearly illustrated in Figure 1.

In order to remove the plug it is necessary to employ the proper plug key 2, as shown in perspective in Figure 4.

The plug key 2 has a longitudinal shank portion 12 and a finger manipulating portion 13 at its outer end. The shank 12 has a straight upper edge 14 and a beveled or tapering end 15 which constitutes a cam and which when the key 2 is inserted functions to lift all of the tumblers 4 and support them.

The shank 12 on its lower edge at its forward portion is recessed as shown at 16 so as to accommodate a raised portion 17 on the upper edge of the plug 1 and allow the shoulders 18 and 19 on the key 2 and plug 1, respectively, to engage each other, so that when the key is withdrawn it will carry the plug with it.

The proportions of these shoulders are somewhat exaggerated for purposes of clearness as only a slight engagement is necessary; and also some slight freedom of movement is necessary for the key to fall into locking en-

gagement with the plug, but this is very slight, and hence for clearness of illustration the proportions and sizes are somewhat exaggerated, but it is of course to be understood that there is a sufficient space for the free entrance of the key to allow it to fall into interlocking engagement with the plug.

While I have illustrated in Figure 1 a plug of a length which will so position the tongue 10 as to support one of the tumblers 4 it is obvious that this tongue may be proportioned longitudinally of the plug so that it may support any desired number or none of the plugs, and by varying the length of the web portion 15 and corresponding length of the shoulder portion 18 of the key a great number of different combinations of plug and key can be provided so that each owner of a plug and key may be protected from unauthorized 20 operation.

When it is desired to secure the lock, the operator merely forces the plug into position, as indicated in Figure 1. This plug cannot be removed except by the use of the proper plug key 2, and it will prevent the use of the ordinary key or master key and will prevent the operation of the lock except by the holder of the proper plug key, who must first insert the same and remove the plug before the ordinary key can be used.

Various slight changes and alterations might be made in the general form of the parts described without departing from the invention, and hence I do not limit myself to the precise details set forth but consider myself at liberty to make such slight changes and alterations as fairly fall within the spirit and scope of the appended claims.

I claim:

40. 1. A key device for use in connection with locks employing tumblers comprising a plug part adapted to be inserted into the key aperture of the lock, said part having a projection adapted to cooperate with a predetermined number of tumblers of the lock to prevent withdrawal or removal of said part and the other part being adapted to interlock with the first named part and to permit the removal of said part, a disk on the outer end of the plug part having an opening adapted to receive the said other part.

55. 2. A plug key of the class described comprising a part adapted to be inserted into a lock employing tumblers and retained against displacement therefrom by a predetermined number of said tumblers and including another part adapted to be inserted into the lock and to cooperate with said first named part and said tumblers to permit withdrawal thereof, a member formed at the outer part of said first part adapted to abut the outer face of said lock and retain said part against predetermined displacement inwardly into said lock, said member also serving to guide

and limit the insertion of said second part into said lock aperture.

3. A plug key of the class described comprising a part adapted to be inserted into a lock and retained against displacement therefrom and another part adapted to be inserted into the lock and cooperate with said first named part to permit withdrawal thereof, both of said parts being provided with interlocking members and the cross section of both said parts cooperatively corresponding with the contour of the key aperture of the lock, a member disposed on the outer end of said first part adapted to cover the lock opening and including an opening corresponding in cross section to said second part of said plug key.

4. A plug key for tumbler locks, said key being composed of two interlocking parts, both of which when placed one upon the other 85 and edge to edge, cooperatively are of a cross section corresponding with the key aperture of a predetermined lock, one of said parts comprising the plug part, said plug part being provided with a member on the outer end thereof to limit the insertion thereof into the opening of the lock, said member being formed with an opening to limit the insertion only of the other of said cooperative parts.
